MECHANISM FOR APPLYING LABELS TO ARTICLES

George W. von Hofe, Bound Brook, N. J., assignor to New Jersey Machine Corporation, Hoboken, N. J., a corporation of New Jersey

Application May 7, 1941, Serial No. 392,271

10 Claims. (Cl. 216—55)

The invention relates to machines for applying labels to articles and more particularly to the application of labels in the form of strips of material having an inherent stiffness tending to maintain said strips of material in a normal flat condition and to restore them thereto.

The invention has for its object the provision of a novel and efficient mechanism whereby application of labels or strips of material of the indicated type is facilitated and simplified.

The invention contemplates particularly a novel mechanism whereby the adhesive application of such labels or strips of material when deformed out of their normal flat condition, to the articles, as exemplified by the application of conventional excise revenue stamps to the ends and sides of bottles and the like, is rendered efficient and certain.

The invention contemplates particularly a novel mechanism whereby existing difficulties inherent in the adhesive application of such labels or strips of material, when deformed out of their normal flat condition, to articles, as exemplified by the application of a conventional revenue stamp to the end and sides of a bottle, are overcome in a simple and efficient manner.

A further object of the invention is to provide a novel and simple mechanism for carrying out the aforesaid application of said labels in an efficient and uniformly effective manner.

Other objects will appear from the description hereinafter and the features of novelty will be pointed out in the claims.

In the accompanying drawings which show an example of the invention without defining its limits,

Fig. 1 is a sectional elevation of a labeling machine provided with the novel mechanism;

Fig. 2 is a fragmentary front elevation of the labeling machine;

Fig. 3 is a detail view of the novel mechanism, and

Fig. 4 is a perspective view illustrating a step in the application of the label or strip of material to an article.

In carrying out the novel application to the articles, the strips *a* of material, such as for instance, conventional excise revenue stamps, are provided with definite folding lines *b* extending transversely of the length of the strips at points spaced apart to an extent corresponding to the end width *c* of the bottle *d* or other article, to divide the strip into an intermediate section *e* and opposite end sections *f* foldably connected therewith at the folding lines *b*. Preferably the

folding lines *b* are produced on strips *a* such as excise revenue stamps, while the latter are being conveyed to the label disposal station. Subsequent to the provision of the folding lines *b* the strip *a* is deposited on the end of the bottle *d* or other article with the intermediate section *e* in registry with said end of the bottle *d* or other article in which position the folding lines *b* are in approximate tangential relation to the bottle 10 end or in a corresponding position on the surface of another article. The one surface of the strip or label *a* is coated with adhesive which may have been applied thereto prior or subsequently to the production of the folding lines *b* on said strip or label *a*. In proper sequence, the opposite end sections *f* are folded, either individually or concurrently, on the folding lines *b* along the opposite sides of the bottle *d* or other article, and pressed into engagement with the bottle *d* or other article to cause said end sections *f* to adhere thereto. The provision of the folding lines *b* on the strip or label *a* makes it definitely certain that the end sections *f* will be folded at right angles to the intermediate section *e* of the strip or label *a* and thereby insure a uniform application of said end sections *f* to the opposite sides of the bottle *d* or other article in matching positions thereon. Without such folding lines *b* the folding of the end sections of the strip or label 20 will be haphazard particularly when the surface of the article such as the top of the bottle *d* is round, and oftentimes results in irregular application of and unsightly appearance of the applied strip or label. In some instances, the method may include the steps of moistening each strip or label *a* on one surface thereof, then applying the coating of adhesive to the opposite surface of the strip or label *a* to render the same adhesive and to further moisten the same. The method in addition may include the steps of again moistening the label or strip *a* coincidentally with its adhesive application to the article, and of applying the pressure to complete said application, in the presence of heat.

For the purpose of illustrating the novel mechanism and its operation in carrying out the novel application to the articles, I have selected a labeling machine designed primarily for adhesively applying strips of material as exemplified for instance by conventional excise revenue stamps, to the tops and opposite side surfaces of bottles or other articles. It will be understood that the illustrated labeling machine is in no sense intended to define the limits of application and use of the novel mechanism.

The illustrated machine comprises a supporting frame 10 of appropriate type and dimensions on which a suitable container or hopper 11 is mounted in position for proper co-operation with the associated elements of the machine. The container or hopper 11 contains a supply of strips of material or labels 12 in the form of an upright stack from the upper end of which successive terminal labels are removed in individual sequence for application to the articles for which said labels 12 are intended. In the instant case, the labels 12 are exemplified by conventional excise revenue stamps, and the articles are exemplified by the bottles *d* to which said labels are adhesively applied so as to extend over the stoppers and along two opposite upright surface portions of said bottles *d* in the well-known way. When fully applied, the labels 12 are thus of inverted U-shape and in the conventional manner prevent tampering with the stoppers of said bottles *d* without damage to the labels 12. Because of the inherent stiffness of the strips or labels 12, as exemplified by the aforesaid revenue stamps, and the resultant tendency to return to a flat condition, the aforesaid application of said labels 12 in the manner indicated above, presents difficulties which are efficiently overcome with the novel method and in the instant mechanism as will be fully set forth hereinafter.

Any suitable provision may be made for periodically restoring the upper end of the stack of labels 12 to a predetermined level in proper operative relation to the associated elements of the machine. As the means for effecting the aforesaid restoration does not per se constitute a part of the novel arrangement, only a fragmentary exemplification thereof is included in the illustrated machine. With the type of mechanism for periodically elevating the stack of labels 12, the container or hopper 11 is provided with a vertically adjustable bottom on which the stack of labels 12 is supported. The aforesaid bottom of the container or hopper 11 is carried by a vertical rack which meshes with a pinion fixed upon a shaft 13 journaled on the frame 10 in any conventional manner. A ratchet wheel 14 is also secured upon the shaft 13 and may be intermittently operated by means of a pawl 15 and held against unintentional return movement by a stop-pawl 16 suitably pivoted upon the frame 10. The pawl 15 is pivotally mounted upon an operating member 17 which itself is mounted to rock upon the shaft 13 and in practice carries a roller arranged to be operatively acted upon by a suitable cam mounted on the frame 10 in any convenient manner, for instance as shown in my Patent No. 2,227,816 of January 7, 1941. The member 17 is normally held against operation by means of a projection 18 in cooperation with a shoulder 19 formed on a controlling member 20 which is tripped to release said member 17 when the stack of labels 12 has decreased in height to a predetermined point. An arrangement of the kind described is shown in my aforesaid Patent No. 2,227,816.

The stack elevating mechanism is controlled by means of a feeler 21 arranged to engage the upper end of the stack of labels 12, and vertically slidable in an upright guide 22 on the frame 10; the feeler 21 is pivotally connected at 23 with a bell-crank lever 24 fixed upon a shaft 25 journaled on the frame 10 and provided with a roller 26 arranged in operative relation to a cam 27. The latter is secured upon

5 a rock-shaft 28 suitably mounted on the frame 10.

Because of the inherent stiffness of the labels 12, as exemplified by conventional excise revenue stamps, it may be desirable to soften the labels 12 in order to facilitate the application to the articles exemplified by the bottles *d*. For this purpose, the terminal labels 12 in the supply stack may be moistened on the face thereof in any suitable manner, for instance, by means of a spray from the feeler 21, as shown in my Patent No. 2,238,436 of April 15, 1941.

In the machine as illustrated, the means whereby individual labels 12 are successively removed from the top of the stack in the container or hopper 11, and transferred therefrom to the point of application to the articles exemplified by the bottle *d*, is of the suction operated or vacuum type, and per se may be of any suitable construction. As shown, the label transferring means consists of a carriage 29 slidably mounted for reciprocation on a horizontal guide rail 30 supported on the frame 10 in any convenient manner. In the illustrated example, the means whereby the carriage 29 is reciprocated on the rail 30 comprises an arm 31 fixed upon the shaft 28 and having its free end pivotally and yieldingly connected with a coupling rod 32 which in turn is pivotally connected at 33 with a lug 34 forming part of or fixed upon the carriage 29, as shown in Fig. 1.

The mechanism whereby the shaft 28 is rocked on its axis to correspondingly operate the arm 31 and thereby effect the reciprocation of the carriage 29 on the rail 30, may be similar to that shown in my previously mentioned Patent No. 2,227,816.

The carriage 29 supports a member 35 capable of vertical reciprocation thereon and provided at its lower end with a suction head 36 of any suitable type and having a suction nipple 37 for accommodating one end of a suction hose 38, as illustrated in Fig. 1. The suction hose 38 is connected with a source of suction suitably controlled in any conventional manner to provide the desired results.

The member 35 is vertically movable on the carriage 29 at one end of the reciprocation thereof to pick up a terminal label 12 from the top of the stack in the hopper 11, and at the other terminal of said reciprocation to dispose of the picked up label for application to a bottle *d* or other article. During the movement of the carriage 29 from the label pick-up station to the label disposal station, the member 35 is held against downward movement on the carriage 29 by means of a roller 39 which travels along a fixed rail 40 recessed at the proper points to permit the desired downward movements of the member 35 and with it the suction head 36. Any suitable mechanism may be provided for operating the member 35 and suction head 36 in vertical directions, such as for instance disclosed in my aforesaid Patent No. 2,227,816.

In the instant machine, the labels 12 picked up successively by the suction head 36 from the stack in the hopper 11 are provided with a coating of adhesive on their lower surfaces during the transfer of said labels from the pick-up station to the disposal station. This adhesive coating, in addition to its other functions, may serve to moisten the reverse surface of each label subsequently to moistening of the face of said label by the spray from the feeler head; the softening effect of said spray may thus be augmented by

the softening action of the adhesive coating whereby the inherent stiffness of said labels 12, exemplified by conventional revenue stamps, may be still further reduced and said labels may be converted to a condition of flexibility which facilitates their application to the bottles *d* or other articles.

For the purpose of applying said coating of adhesive to successive labels 12, the machine includes adhesive applying means consisting, for instance of an adhesive applying roll 41 suitably mounted in the machine in tangential receiving relation to a suitably mounted adhesive distributing roll 42 which dips into a supply of adhesive in a container 43 fixed in place in any convenient manner. The applying roll 41 is so located that a label 12 carried by the suction head 36 will pass in progressive tangential engagement with said roll 41 during the travel from the pick-up station to the disposal station; the arrangement is such that during a return travel of the carriage 29 the suction head 36 will be elevated and will pass over and above said applying roll 41 and accordingly will not engage the same.

The labeling machine in its illustrated form includes supporting means located at the disposal station for receiving successive adhesive coated labels 12 from the suction head 36 and for supporting said labels 12 in predetermined applying relation to the bottles *d* or other articles. In the selected example the aforesaid supporting means includes carrying members 44 located in spaced registry at a common level for instance, as shown in Fig. 2. During an operative cycle of the machine an adhesive coated label 12 is deposited by the suction head 36 upon said carrying members 44 with the opposite end portions of said label 12 in temporary adhesive connection therewith and the intermediate portion of said label 12 extending between and spanning the space between said carrying members 44. The arrangement is such that the label 12 will be supported in predetermined label applying relation to the article to which it is to be applied, as for instance, at a level coincidental with the upper surface of the stopper whereby the bottles *d* are closed; as illustrated in Fig. 2; because of the tacky condition of the adhesive coating at this stage, the label 12 at its opposite ends will adhere to the carrying members 44 in temporary adhesive connection therewith and accordingly will be supported in predetermined applying relation to the particular bottle *d* or other article.

As shown in Figs. 1 and 2, the carrying members 44 comprise integral parts of a depending web 45 which extends between and is carried by levers 46 fixed upon and projecting upwardly from a rock shaft 47 suitably journalled on the frame 10. For the purpose of adjusting the carrying members 44 from an operative label applying position to an inoperative position to permit the bottles *d* or other articles to be brought to labeling position without interference, any suitable means may be provided for rocking the shaft 47, for instance as shown in my previously mentioned Patent No. 2,238,436. A spring 48 may be connected with one of the levers 46 and with a pin on the frame 10 for maintaining the carrying members 44 in their normal operative position and for returning said members thereto.

In the illustrated machine, the bottles *d* or other articles to be labeled are conveyed in intermittent steps over a given path which includes the labeling station at which the initial appli-

cation of the labels takes place. For this purpose the illustrated machine is provided with a carrier comprising a turntable 49 having a plurality of upright receptacles 50 located circumferentially at regularly spaced intervals and shaped and dimensioned to accommodate the bottles *d* and to hold them in upright positions on said turntable 49 as indicated by dotted lines in Fig. 1.

- 10 In the example of the machine selected for purposes of illustration and description, the carrier or turntable 49 is provided with a plurality of receptacles 50 located at equally spaced intervals circumferentially of the turntable 49. In the operation of the machine, the turntable 49 is intermittently rotated in successive steps, for instance as shown in my previously mentioned Patent No. 2,238,436, whereby the receptacles 50 are progressively brought to successive stations of the machine at which successive steps in the operative cycle are performed, for instance as disclosed in said Patent No. 2,238,436.

In addition to the parts so far described, the machine includes a first applying means for effecting the initial application of a label 12 to a bottle *d* or other article, and located at a first applying station as in my Patent No. 2,238,436. As shown, this applying means comprises a slide-member 51 slidably mounted in a vertical guideway fixed upon the frame 10 in any convenient manner. The slide-member 51 carries a guide bracket 52 which preferably is removably fixed in place. A pressure slide 53 carrying a suitable pressure device 54 at its lower end is slidably mounted in said guide bracket 52 in surface engagement with the slide-member 51 and slidably relatively thereto as will appear more fully hereinafter. A spring 55 has its one end connected with the guide bracket 52 and its other end attached to the pressure slide 53 and causes the pressure device 54 to develop an operative pressure on the label 12 in the application thereof to the bottle *d* or other article, as will be more clearly described hereinafter. In addition to the above, the applying means includes pressure levers 56 pivotally mounted at 57 and continued in the form of oppositely directed arms 58 which intersect each other as shown in Fig. 2, and terminate in depending ends 59 to which pressure pads 60 of suitable material, preferably yielding in character, are secured in any convenient manner. The ends 59 are preferably constructed in a manner to supply liquid to the pressure pads 60 to render the same moist, and, as shown, are provided with nipples 61 for the accommodation of tubes 62 connected with a suitable source of moistening liquid. In the preferred arrangement the pressure pads 60 in addition to being yielding in character, may be shaped at least at their active surfaces to fit the surface of the bottles *d* or other articles to which the labels 12 are to be applied.

In any case, the pressure levers 56 may be provided at their upper ends with rollers 63 and preferably are connected at said upper ends by a spring 64 tending to force the pressure pads 60 toward each other.

The guideway, as shown in Fig. 2, includes bearing lugs 65 in which pivot pins 66 are journalled, said pivot pins 66 carrying operating levers 67 and 67^a which control the operation of the pressure levers 56 and the pressure pads 60 thereof. The operating levers 67 and 67^a throughout a portion of their length are provided with outer side flanges 68 extending for a predetermined dis-

tance from their lower ends, and with opposed inner side flanges which extend in parallel spaced relation to the outer side flanges 68 and upwardly beyond the same to provide surfaces along which the rollers 63 of the pressure levers 56 travel, in the operation of the mechanism as will be described more fully hereinafter. With this construction, the operating levers 67 and 67^a at their lower end portions are channelled in cross-section for the accommodation of the aforesaid rollers 63 to thereby operatively connect the pressure levers 56 with the operating levers 67 and 67^a respectively, at a given period in the operative cycle of the machine, as will be more particularly set forth further on in the description.

The operating levers 67 and 67^a are coupled together for coincidental operation in the intended manner in any suitable way. For instance, as shown in Fig. 2, said levers 67 and 67^a are provided respectively with lugs 69 and 70 which project laterally from said levers in directions toward each other, and in superimposed overlapping registry with each other. In the preferred arrangement, one of said lugs 69 or 70 carries an adjustable projection adapted to engage the other lug; in the illustrated construction, the adjustable projection is exemplified by a screw 71 threaded in the lug 70 and bearing against the lug 69 as shown in Fig. 2. A spring 72 having its one end connected with an extension of the lug 70 and its other end attached to an ear 73 on the operating member 67 serves to yieldingly maintain said screw 71 or its equivalent in bearing contact with the lug 69.

Any suitable mechanism may be provided for actuating the levers 67 and 67^a and their associated elements in operative synchronism with the other parts of the machine. For instance, as shown in the selected example, the operating member 67 may constitute an integral part of 40 or be connected with an arm 74 having a forked free end in which a bearing pin 75 is pivotally mounted. A connecting rod 76 is slidably mounted in said bearing pin 75 and is threaded at its upper end for the accommodation of nuts 77, 45 against one of which one end of a spring 78 bears; the other end of said spring 78 engages the bearing pin 75 to thereby provide a resilient connection between said arm 74 and connecting rod 76. The lower end of the latter is operatively connected with suitable operating mechanism, for instance, as disclosed in my Patent No. 2,238,436.

In the operation of the machine, the slide member 51 is slidably shifted in its guideway to correspondingly actuate the pressure slide 53 and pressure levers 56 in synchronised operative steps by means of suitable mechanism. The latter in its illustrated form includes a bracket 79 loosely mounted on the shaft 28 and having spaced arms 80 the one of which has its free end preferably rounded and located in a recess 81 formed in the slide member 51 for instance near its upper end. An actuating member 82 is pivotally connected at 83 with the other arm 80 of the bracket 79, said arm preferably being provided with a slot 84 in which the pivot 83 is adjustably mounted to enable the operative rocking movements of the bracket 79 to be selectively adjusted. The actuating member 82 is connected with suitable operating means, for instance as shown in my previously mentioned Patent No. 2,238,436.

The machine furthermore includes additional applying means operating substantially to the first supplying means, and operative for instance at a second label applying station as in my Pat-

ent No. 2,238,436. As shown in Fig. 2 of the drawings, the aforesaid additional applying means may correspond in construction and operation substantially to the first applying means located at the first applying station. In the second applying means suitable provision is preferably made in any convenient manner for heating the pressure pads for the purpose to be more fully described hereinafter; in the selected example, the heating means is diagrammatically illustrated as an electrical device connected with a source of electricity by means of the wires 85 in Fig. 2.

The machine may be operatively driven in any convenient manner, for instance as shown in my Patent No. 2,238,436 referred to hereinbefore.

The novel mechanism whereby the strips or labels 12 are provided with transverse folding lines b at points spaced apart to a predetermined extent generally corresponding to the surface or end width of the article d may be of any suitable character and may be located at a convenient point in the machine for co-operation with the other elements thereof in predetermined and proper timing. In the preferred arrangement, the aforesaid mechanism is located and designed to produce the transverse folding lines b on the strips or labels 12 while the latter are in place on the suction head 36 and being transferred thereby to the label disposal station.

In the illustrated example, the novel mechanism comprises a pair of co-operating wheels 86 having peripheral edges designed to produce the folding lines b, for instance, by creasing the strips or labels 12 without however at any time cutting entirely through said strips or labels 12. The wheels 86 are mounted on a shaft 87 preferably so as to be adjustable lengthwise thereof and may be fixed in adjusted positions on said shaft 87 by set screws 88 or the like. If desired, provision may be made to insure rotation of the wheels 86 with the shaft 87 as by means of keys 89 on the shaft and co-operating keyways on the wheels. The shaft 87 may be journalled in suitable bearings 90 on the frame 10 of the machine and may be driven in any convenient manner. In order to secure the production of the folding lines b in the most efficient manner and to avoid the possibility of cutting through the strips or labels 12, the active face of the suction head 36 or its equivalent preferably is provided with surface creasing grooves 36^a located so as to register with the peripheral edges of the wheels 86.

As shown in Fig. 1 of the drawings, the wheels 86 are located at a point between the container or hopper 11 and the adhesive applying roll 41 with their peripheries in proper co-operative relation to the creasing grooves 36^a of the suction head 36 and to the strip or label 12 as the latter is transferred by said suction head 36 toward the label disposal or applying station of the machine. The shaft 87 is operatively connected with adhesive applying roll 41 by means of sprockets 91 and a connecting sprocket chain 92, it being understood that the adhesive rolls 41 and 42 are suitably driven and accordingly transmit rotary motion to said shaft 87 and wheels 86. It will be obvious that the wheels 86 and their associated elements may be otherwise located in the machine than is shown in Fig. 1 and be otherwise driven than is disclosed therein.

In describing the operation of the machine and the novel mechanism embodied therein, it will be assumed that labels 12 exemplified by conventional excise revenue stamps are being applied

to the tops and necks of bottles *d*, it being understood that this is done for convenience and with no intent to thereby define or limit the range of utility of the novel mechanism.

With the parts in a position shown in Fig. 1, the feeler 21 is in contact with the current terminal label 12 and the top of the supply stack; at this stage, the upper surface of said terminal label 12 may be in the process of being moistened by the spray of liquid which issues from the feeler. By the action of the cam 27 on the roller 26 and bell-crank lever 24, the feeler 21 is moved up and down in predetermined timing with the other steps in the operative cycle of the machine, and at the proper moment is elevated in the guide 22 to move the feeler 21 upwardly away from the supply stack of labels 12. As this upward movement takes place, the spray of liquid issuing from said feeler is automatically shut off.

In proper operative synchronism with the above steps, the suction head 36 is lifted on the carriage 29 to a level above the adhesive applying roll 41 and above the level of the creasing wheels 36. In Fig. 1 it may be assumed that the suction head 36 is being raised subsequent to the deposit thereby of a label 12 on the carrying members 44 in position for application to a bottle *d* or other article. In such raised condition of the suction head 36 the carriage 29 is shifted to the right on the rail 30 to bring the elevated suction head 36 to the pick-up station in vertical registry with the supply stack of labels 12 in the hopper or container 11.

In proper timing, the suction head 36 is moved downwardly on the carriage 29 into surface contact with the current terminal label 12 at the top of the supply stack, which terminal label 12 may previously have received an initial moistening by the spray from the feeler 21. At this stage, suction is automatically developed in the suction head 36 and the latter is raised on the carriage 29 to thereby pick up or remove said terminal label 12 from the supply stack. The label 12 thus carried on the suction head 36 is transported thereby toward the left in Fig. 1 by the shifting of the carriage 29 along the rail 30 and brings said label into operative relation with the creasing wheels 36 and causes the latter to force said carried label 12 into the creasing grooves 36a and thereby produce the folding lines *b* transversely of the carried label as the latter is progressively carried along by the suction head 36. Subsequently to the production of the folding lines *b* on the carried label 12, the latter will be moved in progressive tangential contact with the adhesive applying roll 41 to receive therefrom a coating of adhesive which, in addition to its other functions, serves to moisten the lower surface of said label. The movement of the carriage 29 and its associated parts is continued until the suction head 36 with the label 12 thereon is in vertical registry with the carrying members 44 at the label applying station of the machine.

In the meantime a capped bottle *d* has been placed in upright position in a receptacle 50 and by the operation of the turntable 49 is brought to the label applying station of the machine. In the illustrated example the arrangement is such that at this stage the capped end of said bottle *d* is beneath and in registry with approximately the intermediate section *e* of the label 12 so that the latter is supported in symmetrical applying relation to said capped end of the bottle *d*.

In proper operative sequence, the arm 80 is 75

operated to cause the slide member 51 to move downwardly in its guideway and to bring the pressure device 54 into contact with the intermediate portion *e* of the label 12 which is forced downwardly into contact with the capped end of said bottle *d* whereupon the downward movement of the pressure device 54 will be arrested. The slide member 51 will however continue to move downwardly independently of and relatively to the pressure slide 53, and the spring 55 will thereby be stretched under tension which is transmitted to the pressure slide 53 and pressure device 54 and causes the latter to firmly press the intermediate portion *e* of the label 12 into adhesive engagement with the capped end of the bottle *d* and holds said label in place thereon. In the continuing operation of the mechanism the pressure levers 56 will be coupled to the operating levers 67 and 67a. As said pressure members 56 thus travel downwardly, the outer end sections *f* of the label 12 will be engaged and withdrawn thereby from the carrying members 44 and will be folded upon the folding lines *b* downwardly along the opposite sides of the neck of the bottle *d* in uniform, corresponding relation thereto; at this stage, the pressure pads 60 are correspondingly located upon said opposite sides of the bottle neck.

At the proper time, the operating levers 67 and 67a are actuated to operate the pressure levers 56 in a manner to shift the pressure pads 60 toward each other. The downwardly bent or folded outer end sections *f* of the label 12 are thereby brought into engagement with the neck of the bottle *d* upon opposite sides thereof in substantially symmetrical relation to each other and as the operative action continues are pressed into adhesive engagement therewith by said pressure pads 60.

As previously stated, the pressure pads 60 may be moistened so that the label 12 which previously may have been moistened at the pick-up station and by the coating of adhesive applied by the roller 41 is again moistened by said pressure pads 60 at this stage; the latter moistening preferably takes place coincidentally with the application of the end sections *f* of the label 12 to the bottle neck. The stiffness normally inherent in said label 12 is thereby still further reduced so that the label may be manipulated in the indicated manner with its tendency to spring back to straight even form reduced to a minimum. This tendency is still further removed by the folding lines *b* which in some instances make the moistening of the labels as hereinbefore described either wholly or in part unnecessary. Subsequently to these operative steps the additional applying means referred to hereinbefore is operated to complete the adhesive application of the label to the bottle *d*. As previously stated this final pressure is applied in the presence of heat and thereby will quickly remove the previously applied moisture from the label but at the same time will quickly and firmly set the adhesive coating of said label 12.

When the operations of applying the label has been completed, the turntable 49 will be rotated to transfer the finally labeled bottle *d* to a position for removal from the machine by an attendant, or by means of suitable automatically operating means.

With the addition of the novel mechanism for producing the folding lines *b* to the machine, the latter is rendered particularly effective in applying labels which are inherently stiff and

have a tendency to remain in and return to a normal flat condition. The production of the folding lines *b* divides the labels into individual sections which are foldably connected with each other and thereby have the inherent tendency of the label as a whole to return to and remain in a normal flat condition neutralized.

The mechanism for producing the folding lines *b* may be adjusted to vary the location of said folding lines and the distance between the same in accordance with the dimensional and other requirements of the articles to which the labels are to be applied. In any case, by forcing or indenting the labels into the creasing grooves 36^a of the suction head 36 while the latter carries and transports said labels toward the label disposal station of the machine, perfect folding lines *b* are produced on said labels, and at the same predetermined registration between the article such as the bottle *d* and the label to be applied thereto is definitely assured.

The aforesaid folding lines *b* enable the end sections *f* of the labels to be readily and uniformly bent relatively to the intermediate section *e* thereof into symmetric relation to the article *d* for symmetric application thereto to provide labeled articles which are slightly and uniform in appearance.

Various changes in the specific forms shown and described may be made within the scope of the claims without departing from the spirit of the invention.

I claim:

1. A machine for applying strips of material to articles comprising means for producing transverse folding lines on said strips at spaced points thereof to divide said strips into intermediate sections and opposite end sections foldably connected therewith, means for depositing the intermediate section of a strip on an article, and means for folding the end sections of said strip on said folding lines along said article and for applying said end sections thereto.

2. A machine for applying strips of material to an end and opposite sides of articles comprising a support for said articles at an applying station, means for producing transverse folding lines on said strips at points spaced apart to an extent corresponding to the end width of said article to divide said strips into intermediate sections and opposite end sections foldably connected therewith, means for depositing a strip on an article at said applying station with the intermediate section of said strip in registry with the end of said article, and means for folding the end sections of said strip on said folding lines along the opposite sides of said article and applying said end sections thereto.

3. In a labeling machine, means for conveying

a label over a predetermined path for application to an article, and means for providing said label with spaced folding lines during the conveyance thereof by said conveying means.

4. In a labeling machine, means for conveying a label over a predetermined path for application to an article, means for providing said label with spaced folding lines during the conveyance thereof by said conveying means, and means for applying adhesive to a surface of said label.

5. In a labeling machine, means for conveying labels over a predetermined path for application to articles, means for moistening said labels to soften the same, and means for providing said labels with spaced folding lines during the conveyance thereof by said conveying means.

6. In a labeling machine, means for conveying labels over a predetermined path for application to articles, means for moistening said labels to soften the same, means for providing said labels with spaced folding lines during the conveyance thereof by said conveying means, and means for applying adhesive to a surface of said labels.

7. In a labeling machine, the combination of a container for a supply stack of labels, means for supporting articles in label receiving position, a pick-up device for removing labels from said supply stack and transferring said labels into applying relation to said articles, means located in the path of transfer of said labels for providing the latter with spaced folding lines, and means located in said path of transfer for applying adhesive to a surface of said labels.

8. In a labeling machine, means for supporting a bottle in an upright label receiving position, means for producing spaced folding lines on a label to divide the same into an intermediate section and opposite end sections foldably connected therewith, means for applying adhesive to said label, means for applying the intermediate section of said label to the upper end of said bottle, and means for folding the opposite end sections on said folding lines downwardly along the neck of the bottle and adhesively attaching said end sections thereto.

9. In a labeling machine, transporting means for conveying a label over a predetermined path for application to an article, said transporting means being provided on its label carrying face with spaced creasing grooves, and means for forcing the carried label into said creasing grooves to provide said label with spaced folding lines.

10. In a labeling machine, a suction head adapted to support and carry a label and provided with creasing grooves into which a label carried by said suction head may be indented to provide said label with folding lines.

GEORGE W. VON HOFE.
